ILLUMINATING APPARATUS

Original Filed Oct. 15, 1931 2 Sheets-Sheet 2

UNITED STATES PATENT OFFICE

FRANK NEWMAN, OF BRONX, NEW YORK

ILLUMINATING APPARATUS

Application filed October 15, 1931, Serial No. 569,051. Renewed May 29, 1933.

This invention relates to illuminating apparatus, and has for one of its objects to provide a novel and simple apparatus of this character which shall be adapted to produce 5 multi-colored light effects of such pleasing character as to adapt it to be used for the purpose of attracting attention to the display windows of stores and for the purpose of illuminating ball rooms and the like.

10 To attain the foregoing and other objects, the nature of which will appear as the description proceeds, the invention comprehends the provision of an illuminating apparatus which will embody a multi-mirrored reflector, 15 means by which the reflector may be secured in a vertical position to a wall or the like, or in a horizontal position to a ceiling or the like, a shaft axially related to and rotatably supported by the reflector, an incandescent 20 electric lamp carried by the shaft for rotation therewith, a globe carried by the shaft in surrounding relation to the lamp for rotation therewith and having differently colored lenses and openings between the 25 lenses, means for rotating the shaft, and means for supplying the lamp with current.

The invention is hereinafter more fully described and claimed, and illustrated in the accompanying drawings, wherein:

30 Figure 1 is a sectional view taken on a plane extending vertically and centrally through an illuminating apparatus constructed in accordance with my invention;

35 Figure 2 is a sectional view on a reduced scale taken on the vertical planes indicated by the line 2-2 of Figure 1;

40 Figure 3 is a view in rear elevation of a fragmentary portion of the apparatus illustrating the means for rotating the shaft and the lamp and globe carried thereby, and also illustrating the means through the medium of which the lamp is supplied with current;

45 Figure 4 is a top plan view on an enlarged scale of a fragmentary portion of the lamp globe illustrating the manner in which the colored lenses are maintained in globe formation, and

50 Figure 5 is a detailed sectional view taken on the plane indicated by the line 5-5 of Figure 1.

The illuminating apparatus comprises brackets 1 and 2, which are arranged in spaced parallel relation and which are of substantially inverted U-form in side elevation. The rear side bars 3 and the front side bars 4 of the brackets 1 and 2, are provided at their lower ends with angular extensions 5 and 6, respectively, which are apertured for the reception of attaching screws 7 or the like. A plate 8 supported by the brackets 1 and 2, 55 has its ends positioned upon and secured, as at 9, to the top bars 10 of the brackets.

A reflector 11 consisting of a sheet metal shell 12, and an inner series of mirrors 13 and an outer series of mirrors 14 secured 60 within the shell, is secured through the medium of the shell to the front bracket bars 4. These bracket bars are curved longitudinally for the greater portion of their 65 length to receive the lower portion of the reflector shell 12 which is secured thereto, as at 15. The series of mirrors 13 are angularly related to the series of mirrors 14, and the mirrors of the respective series are 70 angularly related.

75 The reflector 11 is positioned at the front side of and extends above the support consisting of the brackets 1 and 2 and the plate 8, and it is provided at its axial center, which is located above the support, with a bearing sleeve 15 secured to and extending rearwardly from the reflector shell 12. A hollow shaft 16 is journaled in the bearing sleeve 15, and extends forwardly and rearwardly 80 beyond the sleeve. The shaft 16 is held against endwise movement with relation to the bearing sleeve 15 by a collar 17 and a worm gear 18. The collar 17 is secured to the shaft 16 and bears against a flange 19 which is carried by the front end of the bearing sleeve and through the medium of which the bearing sleeve is fixed to the reflector shell 12. The gear 18 is fixed to the rear end 85 of the shaft 16 and bears against the corresponding end of the bearing sleeve 15.

90 A socket 20 of insulating material is screw threadedly engaged, as at 21, with the front end of the shaft 16, and is provided with a metal bushing 22 and a central contact 23. Contact rings 24 and 25 are mounted upon 95 100

the rear side of the gear 18 in a concentric relation thereto and to each other. The contact rings 24 and 25 are insulated from each other and from the gear 18 by a ring of insulation 26 which is suitably secured to the gear and to which the contact rings are suitably secured. A conductor 27 is connected to the contact ring 24 and to the socket bushing 22, and a conductor 28 is connected to the contact ring 25 and to the socket contact 23. The socket bushing 22 is screw threaded for the reception of the base 29 of an incandescent electric lamp 30.

The lamp 30 which extends forwardly from the shaft 16, and is located forwardly beyond the reflector 11, is surrounded by a globe 31 consisting of colored lenses 32. Some of the lenses 32 are of elliptical contour, others of angular contour and others of circular contour. The lenses 32 are arranged in annular series, each series may consist of lenses of the same or different contours, the lenses of each series are of different colors and the lenses of the respective series are so relatively arranged that no two lenses of the same color are located directly opposite each other. The lenses 32 are each mounted in a light metal frame 33. The lens carrying frames 33 are soldered or welded together, as at 34, to secure the lenses in globe formation. The lens carrying frames 33 are so secured together as to provide openings 35 between the lenses.

The foremost series of lenses 32 has its front side closed by a colored lens 36 which is also mounted in a frame soldered or welded to the frames of the foremost series of lenses. A pin 37 secured to the lens 36 in alignment with the longitudinal axis of the globe 31, extends forwardly from the globe, and is provided at its front end with a transparent disk 38 which may be a trade name, an advertising slogan, a picture, or the like. The globe 31 is provided at its rear end with a sleeve 39 which surrounds and is screw threadedly engaged with the socket 20, the sleeve securing the globe to the socket for rotation with the lamp 30, and the pin 37 securing the disk 38 to the globe for rotation therewith.

An electric motor 40 is provided to effect the rotation of the shaft 16 and consequently the rotation of the lamp 30, globe 31 and disk 38. A worm pinion 41 fixed to the armature shaft 42 of the motor 40, meshes with the worm gear 28 to effect a driving connection between the motor and shaft 16. The motor 40 is mounted upon and suitably secured to the plate 8 at one side of the gear 28, and its armature shaft 42 and pinion 41 are located at the lower side of the gear. A block 43 of insulating material is positioned upon and suitably secured to the plate 8 directly below the pinion 41, and brushes 44 in the form of leaf springs are secured to

and extend upwardly from the block 43. A switch 45, which is mounted upon and suitably secured to the plate 8, and which is adapted to be secured by a cord 46 to an electric outlet socket or the like, is connected by conductors 47 to the brushes 44, and the brushes 44 contact with the conductor rings 24 and 25 to the end that the lamp 30 may be supplied with current.

In practice, the apparatus may be mounted in a display window of a store with its reflector 11 in a vertical position and its globe 31 in a horizontal position, or it may be mounted in a ball room or the like, with its reflector in a horizontal position and its globe 31 in a vertical position. During the operation of the apparatus, the light rays from the lamp 30 will pass through the differently colored lenses 32 and through the openings 35 between the lenses, and the colored and uncolored light rays will be directed downwardly or forwardly by the reflector 11. Some of the light rays will be reflected through the disk 38 and illuminate in different colors the advertising or decorative matter borne by the disk. As the lenses 32 are of different colors, and as they, together with the disk 38, are rotated with relation to the reflector 11, there will be produced a multi-colored light effect of very pleasing character. It will be understood that the rotation of the lamp 30, the globe 31, and the disk 38 is effected through the medium of the motor 40, and that the lamp is supplied with current through the medium of the cord 46, conductors 47, brushes 44, rings 24 and 25, and conductors 27 and 28.

While I have described the principle of the invention, together with the structure which I now consider the preferred embodiment thereof, it is to be understood that the structure shown is merely illustrative and that such changes may be made, when desired, as fall within the scope of the invention as claimed.

What is claimed is:—

1. An illuminating apparatus of the character set forth, comprising a stationary reflector, a shaft arranged at the axis of the reflector and journaled thereon, an electric lamp carried by and rotatable with the shaft in front of the reflector, a globe secured to the shaft in surrounding relation to the lamp and consisting of differently colored lenses arranged to provide intervening openings therebetween, means for rotating the shaft, means for supplying the lamp with current, and a transparent element secured to and arranged in front of the globe and rotating therewith.

2. An illuminating apparatus of the character set forth, comprising a stationary reflector, a shaft arranged at the axis of the reflector and journaled thereon, an electric lamp carried by the shaft in front of the re-

flector, a globular element consisting of a series of rigid frames rigidly secured to each other and rigidly secured to the shaft in surrounding relation to the lamp, the frames being arranged to provide openings between them, colored lenses carried by the frames, means for rotating the shaft, and means for supplying the lamp with current.

3. An illuminating apparatus of the character set forth comprising a stationary reflector, a tubular shaft extending through the axis of the reflector and journaled therein, a socket of insulating material having screw-threaded engagement with the forward end of the shaft, a metallic lamp supporting

bushing disposed within the socket, an electric lamp engaged with the bushing, a sleeve having screw-threaded engagement with the exterior of the socket, and a globe surrounding the lamp and connected to said sleeve and carried thereby, the globe comprising a series of rigid frames rigidly connected to each other, the frames providing openings between them, colored lenses carried by the frames, means for rotating the shaft, and means for supplying current to the lamp.

In testimony whereof I hereunto affix my signature.

FRANK NEWMAN.
